INSERT FOR CONCRETE WALLS AND THE LIKE

Filed July 11, 1925

UNITED STATES PATENT OFFICE.

FRED W. HONENS, OF STERLING, ILLINOIS.

INSERT FOR CONCRETE WALLS AND THE LIKE.

Application filed July 11, 1925. Serial No. 42,895.

My invention relates to metal anchoring devices which are designed to be applied to cement walls, particularly in the ceilings of horizontal walls, or floors, and such as are commonly termed "inserts" in the cement building art. These inserts, usually formed of cast iron, are placed in the ceiling when it is poured, and are used for the attachment of hangers for shafting, machinery, motors or other electrical apparatus or fixtures, pipes, radiators, trolley tracks, or anything which it is desired to suspend from the ceiling. They may also be used for bolting timbers to the ceiling in the construction of partitions, or for other purposes, or a spaced pair of them may be used in connection with U-bolts formed with heads at the ends of their parallel portions, for use in storing pipe, rods, or similar articles. Various forms of such devices are known in the art, and it is the object of my invention to produce an improved insert, designed to be used in connection with a standard square-headed bolt as a connecting member, and of novel and original construction, which shall be better adapted for the purposes for which it is designed to be used than previous devices known to me, and which because of certain novel features of construction, hereinafter described in detail, will be particularly strong, simple and compact in construction, afford maximum holding strength in the concrete, and afford a convenient and secure anchorage for the devices supported thereby. With the foregoing objects and advantages in view I have designed the novel insert illustrated in the accompanying drawing and hereinafter described in detail, the essential elements of my invention being more particularly pointed out in the appended claims.

In the drawing, Fig. 1 is a side elevation of the insert, the concrete wall about it being shown in section; Fig. 2 is a vertical section in a plane indicated by the broken line 2—2 of Fig. 1; Fig. 3 is a central vertical section in a plane at right angles to the plane of Fig. 2; Fig. 4 is a horizontal section in a plane indicated by the broken line 4—4 of Fig. 3; Fig. 5 is a bottom plan view of the device; and Figs. 6 and 7 horizontal sec-

tions corresponding to Fig. 4 but on a smaller scale, of different modified forms of my invention.

Like reference characters indicate like parts in all the figures of the drawing.

My novel insert may conveniently and economically be formed of cast metal, as cast iron, and consists of a single integral shell having as its top portion a square top plate 1 which overhangs vertical side walls connected at the bottom to a square bottom flange 4 which projects laterally from the side walls. Of the side walls of the insert two adjacent upper walls 5—5, standing at a right angle to each other, extend about half way down from the top plate toward the bottom flange, and diagonally across the insert two other adjacent upper walls, 6—6, standing at the same angle from each other, extend from the top plate to a plane a short distance above the bottom flange. Below the walls 5—5, and offset from them towards the center of the insert the casting is formed with lower walls 7—7 which in the present instance are somewhat rounded at their junction with each other; and below the walls 6—6, and similarly offset towards the center, the casting is formed with two other lower walls 8—8, also rounded at their junction with each other. The outer portion of each upper side wall 5 and corresponding lower side wall 7 is connected with the outer portion of the upper side wall 6 and corresponding lower side wall 8 which stand in planes at right angles to their own planes, by a vertical side wall 9, the two opposite side walls 9 therefore being parallel with each other and being disposed diagonally with respect to the edges of the top plate 1 and the bottom flange 4, as well as the other side walls. In the present instance, though not necessarily, the walls 9 are formed each with a transverse exterior rib 9^a about midway between the top and bottom of the insert.

Inasmuch as the lower side walls 7 and 8 are offset inwardly from the upper side walls 5 and 6, respectively, the width of the side walls 9 is reduced below each offset, and opposite the wall 8 the space within the insert is approximately square in cross section and offset slightly towards the center

of the insert from the square opening between the walls 6—6 and the lugs 10—10.

At the interior shoulder formed by the upper and lower side walls 5 and 7 on one side of the device, the metal of the casting is extended continuous with the shoulder, and continuous with a pair of triangular right angled lugs 10—10 on the opposite side walls 9—9 which rise above the level of the shoulder to form, in connection with the walls 5—5, a squared socket or seat for the head of the standard square-headed bolt A which constitutes the connecting member for suspending the load to be supported by the insert.

The ledge at the bottom of the socket extends around a gap which opens between the outer edges of the lugs 10—10 for the purpose of accommodating the shaft of the bolt.

Diagonally across the insert, and below the level of the seat for the bolt head, the offset arrangement of the walls 6 and 8 forms inside and outside shoulders, similar to those formed by the walls 5 and 7.

The flange 4 of the insert is in the present instance formed with a shallow countersunk recess extending outside the line of the side walls 7, 8 and 9, to receive a closure plug which may be inserted and, if desired, plastered over, in case the insert is installed for future use, and it is desired to close it up until the time for its use arrives.

It will be understood that my novel insert is intended to be moulded in place in concrete or cement flooring in the usual manner, and in practice it is customary to place the inserts in the position on the face of the form and pour the plastic cement around them. To hold them in position during this operation the bottom flange 4 of the insert is formed with notches 12 to engage brads driven into the form.

The overhanging top of the insert, the exterior shoulders midway of the insert at the bottom of the walls 5, the ribs 9^a on the walls 9, and the exterior shoulders near the bottom of the insert below the walls 6, it may here be observed, distribute the weight of the load through the mass of cement most effectively so that maximum load-carrying capacity is attained. These shoulders, moreover, provide convenient faces under which reinforcing rods for the concrete may be placed, if desired.

The inserts being installed as above described, it is obvious that the bolt being held in vertical position with its head uppermost it may be inserted through the approximately square opening at the bottom, raised and moved slightly to the right (as the parts are viewed in Fig. 3), lifted to clear the lugs 10—10, shifted to the left over said lugs and lowered into the socket behind the lugs, where it will be held securely and

prevented from turning by the walls 5—5 and said lugs.

It will be noted that the device is very compact in construction, due to the overlapping or intersecting of the square bolt head 70 seat and the passageway on the other side of the lugs, considering one square as formed by the inner faces of the sides 5—5 and the adjacent faces of the lugs 10—10, extended, and the other square as formed by 75 the sides 6—6 and the other two faces of such lugs, extended. The bolt head is seated in its socket on a ledge which on two sides of the head is directly above the side walls 7—7 and which opposite one-half of each 80 of the other two sides is continuous with the lugs 10—10. An exceedingly sturdy and secure construction is thereby attained.

If desired a nut as indicated in Fig. 2 and marked B, engaging the bolt and bearing through a washer (or directly) against the base of the insert may be employed to positively prevent displacement of the bolt head from its seat, although in many cases this will be wholly unnecessary.

It will be understood that while the construction above described is believed by me to be the best form of my invention, it is susceptible of variation and modification, and in Fig. 6 I have illustrated a modified form of my invention, designed to be used in connection with a bolt having a hexagonal head. In this case the interior angle between the upper side walls 5^a—5^a and 6^a—6^a are arranged at an angle of 120° instead of an angle of 90°, as in the case of the corresponding walls 5—5 and 6—6 of the preferred form of my invention, and the triangular lugs 10^a—10^a are smaller and further apart than the lugs of such preferred form. The side walls 9^b—9^b in this form of my invention are relatively much longer than the sides 9—9 of the preferred form.

In Fig. 7 I have illustrated a second modified form of my invention also adapted for use in connection with a bolt having a hexagonal head, in which a side of the bolt head is arranged to lie against an upper intermediate side wall 15 connecting the upper side walls 5^b—5^b, and the walls 6^b—6^b are similarly connected by an upper intermediate side wall 16. In both of these modifications, the other portions of the insert may be the same as in the preferred form, except as to the necessary modification of proportions.

I claim:

1. An insert adapted to be imbedded in a concrete wall and arranged to removably receive a standard square-headed bolt, said insert consisting of a hollow metallic body formed with a pair of contiguous side walls having their inner faces arranged at a right angle to each other and with a pair of inside lugs having faces standing at a right angle 130

to the faces of said walls, the metal of said body being shouldered adjacent said walls and lugs to form a rectangular seat for the bolt head and being notched between said lugs to removably receive the shaft of the bolt.

2. An insert adapted to be imbedded in a concrete wall and arranged to removably receive a standard square-headed bolt, said insert consisting of a hollow metallic body formed with a pair of contiguous side walls having their inner faces arranged at a right angle to each other, and with a second pair of contiguous side walls having their inner faces similarly arranged at a right angle to each other, and with a third pair of side walls continuous with corresponding walls of said first and second pairs of side walls, said third pair of side walls being formed with inside right-angled lugs and the metal of said body being shouldered adjacent said lugs and said first-mentioned offset with a rectangular seat for the bolt head and being notched between such lugs to removably receive the shaft of the bolt, and the inner faces of said second pair of upper side walls and the meeting faces of said lugs forming a rectangular passageway for the bolt head intersecting the seat for the bolt head, and the inner faces of said first and second mentioned lower side walls forming an approximately square passageway for the bolt head which is offset from said first mentioned passageway toward said bolt head seat.
3. An insert adapted to be imbedded in a concrete wall and arranged to removably receive a standard square-headed bolt, said insert consisting of a hollow metallic body formed with an upper pair of contiguous side walls having their inner faces arranged at right angles to each other, and with a pair of lower side walls offset from said upper side walls, and with a pair of inside lugs rising from the plane of the offset between said upper and lower walls and having faces standing at right angles to the faces of said upper side walls, the metal of said body being formed adjacent said lugs and said offset with a rectangular seat for the bolt head having two sides in line with said lower side walls and being notched between said lugs to removably receive the shaft of the bolt.

4. An insert adapted to be imbedded in a concrete wall and arranged to removably receive a standard square-headed bolt, said insert consisting of a hollow metallic body formed with a pair of upper contiguous side walls having their inner faces arranged at a right angle to each other, and with a second pair of upper side walls having their inner faces similarly arranged at a right angle to each other, and with a pair of lower side walls offset from said first-mentioned pair of upper side walls, and with a second pair of lower side walls offset from said second pair of upper side walls in a lower plane than said first-mentioned offset, and with a pair of opposite side walls extending from top to bottom of the insert and con-

tinuous with corresponding walls of said upper and lower side walls, said opposite side walls being formed with inside right-angled lugs and the metal of said body being formed adjacent said lugs and said first-mentioned offset with a rectangular seat for the bolt head and being notched between such lugs to removably receive the shaft of the bolt, and the inner faces of said second pair of upper side walls and the meeting faces of said lugs forming a rectangular passageway for the bolt head intersecting the seat for the bolt head, and the inner faces of said first and second mentioned lower side walls forming an approximately square passageway for the bolt head which is offset from said first mentioned passageway toward said bolt head seat.

5. An insert adapted to be imbedded in a concrete wall and arranged to removably receive a polygonal-headed bolt, said insert consisting of a hollow metallic body formed with a pair of contiguous side walls having their inner faces arranged angularly to engage faces of the bolt head, and with a second pair of contiguous side walls having their inner faces arranged at a similar angle to each other, and with a third pair of side walls continuous with corresponding walls of said first and second pairs of side walls, said third pair of side walls being formed with inside triangular lugs and the metal of said body being shouldered adjacent said first-mentioned side walls and lugs to form a polygonal seat for the bolt head and being notched between such lugs to removably receive the shaft of the bolt, and the inner faces of said second pair of side walls and the meeting faces of said lugs forming a polygonal passageway for the bolt head intersecting the seat for the bolt head.

6. An insert adapted to be imbedded in a concrete wall and arranged to removably receive a polygonal-headed bolt, said insert consisting of a hollow metallic body formed with an upper pair of contiguous side walls having their inner faces arranged angularly to engage faces of the bolt head, and with a pair of lower side walls offset from said upper side walls, and with a pair of inside triangular lugs rising from the plane of the offset between said upper and lower walls and having faces arranged to engage other faces of the bolt head, the metal of said body being formed adjacent said lugs and said offset with a polygonal sided seat for the bolt head having two sides in line with said lower side walls and being notched between said lugs to removably receive the shaft of the bolt.

7. An insert adapted to be imbedded in a concrete wall and arranged to removably receive a polygonal-headed bolt, said insert consisting of a hollow metallic body formed

with side walls and an overhanging top plate portion, certain of said side walls being offset and arranged to present downwardly facing external shoulders and upwardly facing internal shoulders arranged to form a seat for the head of the bolt, and certain others of said side walls being formed with

internal triangular lugs adjacent said internal shoulders, said lugs extending above the plane of said shoulders and forming with adjoining side faces of said first mentioned certain side walls a polygonal enclosure for the head of the bolt.

FRED W. HONENS.
